COMBINED SURGICAL INSTRUMENT CLEANER AND STERILIZER

George Perkins and David E. Workman, Pasadena, Calif.,
assignors to VERNITRON CORPORATION, Farmingdale, N.Y.,
a corporation of New York

Filed Jan. 27, 1966, Ser. No. 810

Term of patent 14 years

(Cl. D83—1)

FIG. 1

FIG. 2.

FIG. 3.

FIG. 4.

FIG. 1 is a front perspective view of a combined surgical instrument cleaner and sterilizer showing our new design.

FIG. 2 is a left side elevational view thereof.

FIG. 3 is a rear elevational view thereof.

FIG. 4 is a top plan view thereof.

The undisclosed side of the combined surgical instrument cleaner and sterilizer is substantially the same in appearance as the side shown.

The dominant features of my design reside in the portions shown in full lines.

We claim:

The ornamental design for a combined surgical instrument cleaner and sterilizer, as shown and described.
